UNITED STATES PATENT OFFICE

HORATIO L. MILLER, OF WORCESTER, MASSACHUSETTS.

DESIGN FOR A DAUBER.

SPECIFICATION forming part of Design No. 31,973, dated December 12, 1899.

Application filed October 31, 1898. Serial No. 695,138. Term of patent 14 years.

To all whom it may concern:

Be it known that I, HORATIO L. MILLER, a citizen of the United States, residing at Worcester, in the county of Worcester and State of Massachusetts, have invented and produced a new and original Design for a Dauber, of which the following is a specification.

This design relates to daubers, and has for its subject an original and beautiful configuration for such an article.

In my novel design of dauber at one end is represented a portion having at its extremity a straight edge from which diverge plane surfaces bounded by lines extending rearwardly from the straight edge for a short distance at an angle to each other and then merging into the surface of an extension B of the material of the dauber lying to the rearward of the portion A.

In the accompanying drawings is illustrated a device of the class designated, in the configuration of which my design is embodied,

Figure 1 being a view thereof in perspective, Fig. 2 a view in side elevation, and Fig. 3 a similar view looking from top to bottom, Fig. 2.

In the drawings the portion A presents at its extremity a straight edge a^2 , from which diverge plane surfaces bounded by lines $a a'$, extending rearwardly from the straight edge for a short distance at an angle to each other and then merging into the surface of an extension B of the material of the dauber lying to the rearward of the portion A.

Having thus illustrated and described my design fully, that which I claim, and on which I desire to secure protection, is—

The design for the dauber substantially as shown and described.

In testimony whereof I have signed my name to this specification in the presence of two subscribing witnesses.

HORATIO L. MILLER.
